UNITED STATES PATENT OFFICE.

JOSEPH R. LINNEY, OF LYON MOUNTAIN, NEW YORK, ASSIGNEE TO CHATEAUGAY ORE & IRON CO., OF LYON MOUNTAIN, NEW YORK, A CORPORATION OF NEW YORK.

SINTERING MACHINE.

Application filed February 15, 1924. Serial No. 693,009.

To all whom it may concern:

Be it known that I, JOSEPH R. LINNEY, a citizen of the United States, residing at Lyon Mountain, county of Clinton, State of New York, have invented new and useful Improvements in Sintering Machines, of which the following is a specification.

This invention relates to apparatus of the horizontal type for sintering ore and the like, and particularly to an apparatus containing a train of separate pallets or grates adapted to form a continuous moving grate for continuously sintering the ore fed upon it and discharging it upon the completion of the sintering operation.

In earlier sintering machines of the well-known Dwight and Lloyd horizontal type, the separate pallets or grates are adapted to be propelled along an endless track which track has an upper horizontal portion whereon the loaded pallets or grates move during the sintering of the ore and a lower return portion whereon the empty pallets or grates move. The sintered ore is dumped or discharged as the pallets tilt and separate in running around and down the discharge end of the machine from the upper to the lower portions of the track. The pallets are then propelled back empty along the lower return portion of the track to the feed end of the machine where they are elevated up and around the return curve of the track to the upper horizontal portion and to the point of feeding of the ore to be sintered and are then propelled along the upper horizontal or sintering portion of the track to the discharge end of the machine. The operation is continuous. Because of the expansions and contractions of the train of pallets by the heat changes developed in the operation of the machine, the track is made slightly longer than the train of pallets so as to provide an expansion space somewhere along the endless track to prevent breakage. It has been the practise in this horizontal type of machine to provide this expansion space at the discharge end of the machine by allowing the pallets to separate there under the action of gravity in running down around the end of the machine while dumping or discharging. Difficulty has been encountered due to sinter falling between the pallets when they separate and sticking to the pallets at their contacting surfaces and

so preventing their proper contact later on and their proper engagement with the sprocket wheels and thereby causing the machine to wreck itself. For this reason it has been found necessary to have an operator 60 at the discharge end of the machine to remove by means of a poker any sinter so lodging between the pallets. If the operator is not able to keep the pallets on their contacting surfaces entirely clear and clean, 65 the loss in machinery breakage and in shutdown time is or may be heavy.

It is an object of this invention to provide a machine of this general type but containing means for avoiding these objections 70 and for decreasing the expense of operating such machines.

One object of the invention is to provide means whereby the pallets of the train of pallets are kept from separating at the discharge end of the machine and an expansion space is provided at a portion of the track other than the discharge end of the machine.

Another object of the invention is to provide means whereby the train of pallets may be driven wholly from the feed end of the machine and whereby the separate pallets may be reliably and accurately brought into engagement with such driving means.

Further objects of the invention will appear hereafter.

In the accompanying drawing, which forms a part hereof, I have shown in elevation a machine embodying my invention in 90 its preferred form. It consists of a suitable support 1 carrying an endless track 2, upon which a train of pallets or grates 3 (slightly shorter than the track) is adapted to travel, being elevated and propelled by the 95 sprocket wheel 4. Any other suitable driving and elevating means for moving the pallets continuously along the track may be employed. At the feed end of the upper portion of the track is a hopper 6 located over the track for feeding the ore on to the pallets. Any usual igniting means 7 may be employed for igniting the oil under the pallets. Between the feeding hopper and the discharge end of the machine the pallets form a continuous moving grate, the speed of movement and the length of the machine being regulated so as to produce the desired degree of combustion of the ore before its discharge.

- The sinter is discharged as the pallets move down around the discharge end of the machine, but, because of the formation of the lower return portion of the track herein after described, the pallets cannot separate but are held firmly together at and around such discharge end of the machine so that sinter cannot get between the pallets or become lodged between them.
- For this purpose, I form the lower return portion of the track (preferably just before it reaches the sprocket wheel 4) with an upgrade 8 as a retarding means or part of a retarding means and then with a downgrade 9 as an accelerating means. The upgrade 8 produces such resistance to the movement of the train of pallets at the discharge end of the machine that, with the added retarding action of the friction in the portion of the return track between it and the discharge end of the machine, the separation of the pallets in rounding and descending the discharge end is certainly prevented. The accelerating means furnishes the opportunity for separation of the pallets and expansion of the train of pallets and is efficient to bring the separated pallets into prompt and proper contact again, each with the pallet in front of it before reaching the point of engagement with the sprocket wheel 4. To this end the downgrade is preferably shorter and of a sharper pitch sufficient to insure such prompt and proper contact.
- This construction resists the tendency of the pallets to separate, as by gravity or otherwise, at the discharge end of the machine and so prevents sinter getting between the pallets. It allows and achieves separation of the pallets, and so expansion of the train of pallets, after the sinter has been fully discharged. It reunites the separated pallets promptly and in proper contact with one another and in position to properly engage with the sprocket wheel 4.
- In the Dwight & Lloyd sintering machine of the prior art the pallets are driven from both ends. The two sprocket wheels at opposite ends of the machine must be exactly in step with each other in order that the teeth of the sprockets of each wheel shall mesh properly into the pallets. In this machine as stated the expansion space originates at the discharge end of the machine and because of this fact some of the sinter when discharging from the machine may drop into this space to be carried along with the pallets and hold them apart and throw them out of step with the sprocket wheels, causing the machine to wreck itself. To prevent this a man is placed as stated at the discharge end of the machine with a long poker to remove any sinter that may chance to fall between the pallets. Occasionally he is unable to remove all of this sinter.

As a result the machine is wrecked, causing a loss in operation of the machine of many hours duration and an expenditure of money for labor and renewal of parts. My improvement causes the expansion space to originate at a point on the track other than the discharge end of the machine and maintains contact of pallets with one another at that discharge end and throughout the operation of dumping or discharging the sinter so that it is impossible for sinter to drop between the pallets and hold them apart. My improvement also eliminates the necessity of driving the machine from both ends, a construction which is intricate in operation and expensive to manufacture and renew. In machines of this type the separate pallets must return to the driving sprocket accurately so that they may be picked up by the sprocket teeth and to this end the pallets must be properly kept in step and properly presented to the sprocket teeth. My improvement achieves this end by inclining a part 9 of the lower or return portion of the track near the driving end of the machine sufficiently sharply to cause the most sluggish of the pallets to run down regularly and accurately to the driving sprocket wheel. As my improved machine is put in motion the pallets are picked up by the sprockets at the driving end of the machine at the bottom of the downgrade 9 and are elevated and pushed or driven along the upper portion of the track and down and around the discharge end of the machine and until they pass the crest of the upgrade 8 on the lower or return portion of the track and each pallet separates from the train of pallets behind it after it has passed the crest and runs down by gravity to the place of beginning where it is presented properly to mesh with the sprockets of the single driving wheel. This locates the expansion space just over the crest of the upgrade on the return portion of the track, removing it from the discharge end of the machine, and at the same time it reliably and accurately presents the successive pallets to the sprockets of the single driving wheel.

My improvement is of great practical value for it eliminates the expense in construction and the dangers in operation of machines having articulated pallets or pallets driven by endless chains or the like and of machines having driving wheels at both ends of the machine, and at the same time it cuts down the expense of operation and the expense following breakdowns and it eliminates the skewing of pallets which causes wear and tear and it secures accurate meshing of the pallets with the sprockets of the single driving wheel.

While I have shown and described a specific embodiment of the invention, it is

to be understood that the foregoing is illustrative merely and that my invention embraces all devices falling within the spirit and scope of the appended claims.

5. What I claim as new and desire to secure by Letters Patent is:

1. In a sintering machine, a train of separate pallets or grates, an endless track for the same including a loading and combustion portion, a discharge portion, a return portion located below the loading and combustion portion, and means for elevating the pallets or grates from the return portion to the loading portion of the track, said track 15 being longer than the train of separate pallets or grates to provide expansion space for the same, the return portion of the track being provided with means to prevent separation between the pallets or grates at 20 and around the said delivery portion.

2. In a sintering machine, a train of separate pallets or grates and means for propelling the same, an endless track of a length providing expansion space for said train, and an upgrade on the return portion 25 of the track so located and of such length as to keep the pallets or grates in contact at and around the delivery end of the machine.

3. In a sintering machine, a train of separate pallets or grates and means for propelling the same, an endless track of a length providing expansion space for said train, and an upgrade on the return portion of the track having its crest near the feed end of 35 the machine to keep the pallets or grates in contact at and around the delivery end of the machine and to permit separation of the pallets or grates only on said return portion of the track near the feed end of the machine.

4. In a sintering machine, a train of separate pallets or grates, an endless track of a length providing expansion space for said train, means located at the feed end of the 45 machine for positively elevating the pallets or grates and propelling the train of pallets

or grates toward and around the delivery end of the machine, and means including the return portion of the track between the delivery end and the feed end of the machine 50 constructed and arranged to permit separation of the pallets or grates only at a point distant from the delivery end of the machine and to restore contact between them before moving them into engagement with 55 the said elevating and propelling means.

5. In a sintering machine, a train of separate pallets or grates, an endless track of a length providing expansion space for said train, means located at the feed end of the machine for positively elevating the pallets or grates and propelling the train of pallets or grates toward and around the delivery end of the machine the return portion of the track being elevated above its normal 65 level near the feed end of the machine to permit separation of the pallets or grates only at a point distant from the delivery end of the machine and to restore contact between them before moving them into engagement with the elevating and propelling means.

6. In a sintering machine, a train of separate pallets or grates, an endless track of a length providing expansion space for said 75 train, means located at the feed end of the machine for positively elevating the pallets or grates and propelling the train of pallets or grates toward and around the delivery end of the machine, an upgrade on the return portion of the track crest of which is located near the feed end of the machine to keep the pallets or grates in contact at and around the delivery end of the machine, and a downgrade on the return portion of 80 the track nearer the feed end of the machine to move the returning pallets or grates by gravity into position to engage with the elevating and propelling means.

In testimony whereof, I have signed my 90 name to this specification.

JOSEPH R. LINNEY.
